(57) **CLAIM**

The ornamental design for a paint tray caddy as shown and described.

DESCRIPTION

FIG. 1 is a perspective view of a paint tray caddy showing my new design, shown in conjunction with a paint tray that forms no part of the current design; FIG. 2 is a top plan view thereof; FIG. 3 is a bottom plan view thereof; FIG. 4 is a left side elevational view thereof, the opposite side being a mirror image; FIG. 5 is a front elevational view thereof; FIG. 6 is a rear elevational view thereof; and, FIG. 7 is another perspective view thereof, shown in a state of use.

The dash-dash broken lines in FIG. 7 showing a paint tray and paint bucket depict environmental subject matter that form no part of the claimed design.

1 Claim, 7 Drawing Sheets
